Ralph M. Heintz, Cleveland, and Philip F. Scofield, Cleveland Heights, Ohio, assignors to Jack & Heintz, Inc., Bedford, Ohio

Application February 23, 1942, Serial No. 105,954

Term of patent 14 years

To all whom it may concern:

Be it known that we, Ralph M. Heintz and Philip F. Scofield, citizens of the United States and residents of Cleveland, county of Cuyahoga, and State of Ohio, and Cleveland Heights, county of Cuyahoga, and State of Ohio, respectively, have invented a new, original, and ornamental Design for a Reduction Gear Unit, of which the following is a specification, reference being had to the accompanying drawing, forming part thereof.

Figure 1 is a top plan view of a reduction gear unit showing our new design.

Figure 2 is a side elevational view.

Figure 3 is a side elevational view taken at right angles to Figure 2.

Fig. 4 is a bottom plan view.

We claim:

The ornamental design for a reduction gear unit, as shown.

RALPH M. HEINTZ.
PHILIP F. SCOFIELD.
